STOP AND START DEVICE FOR PHONOGRAFS.

No. 441,361.

Patented Nov. 25, 1890.

UNITED STATES PATENT OFFICE.

HENRY D. GOODWIN AND WILLIAM S. BURNETT, OF MILWAUKEE, WISCONSIN.

STOP AND START DEVICE FOR PHONOGRAHS.

SPECIFICATION forming part of Letters Patent No. 441,361, dated November 25, 1890.

Application filed March 4, 1890. Serial No. 342,595. (No model.)

To all whom it may concern:

Be it known that we, HENRY D. GOODWIN and WILLIAM S. BURNETT, of Milwaukee, in the county of Milwaukee, and in the State of Wisconsin, have invented certain new and useful Improvements in Stop and Start Devices for Phonographs; and we do hereby declare that the following is a full, clear, and exact description thereof.

Our invention relates to stop and start devices for phonographs; and it consists in certain peculiarities of construction, as will be fully set forth hereinafter, and subsequently claimed.

In the drawings, Figure 1 is a plan view, partly broken away, of a portion of a phonograph with one form of our device applied thereto. Fig. 2 is a side elevation, partly in section, of the same. Figs. 3, 4, and 5 are details. Fig. 6 is a plan view illustrating another form of our present invention. Figs. 7 and 8 are detail sectional views on the lines 7 and 8 8, respectively, of Fig. 6.

A represents the bed-piece of the phonograph, B the main-shaft feed-screw, and C the hard-wax cylinder mounted on its mandrel on said main shaft, all as common with the phonograph. The end of the feed-screw B is reduced, as shown at a, and carries a collar 30 D, (secured thereto by screw b,) and which has ratchet-teeth formed on its opposite faces, as shown at c and d, respectively.

E is the driving-pulley mounted loosely on the reduced end a of the main shaft, which latter is supported at this end, as shown, by pin or arbor e in bracket-arm f and set-screw f'. This pulley E has a hub F, the inner face of which is provided with a series of ratchet-teeth, as shown at h, for engagement at the proper time with the similar ratchet-teeth d on the adjacent face of the collar D, already named.

G is the shifting-lever, and in the form of our device illustrated in the first sheet of our drawings is shown provided with a couple of elongated slots g g to receive the shanks of screws g' g', by which it is secured on the upper surface of the bed-piece A, and said lever carries at one end a spanner G', which in said form of our invention is received in a groove f² in the hub F of pulley E. The other end

of this form of lever G carries a vertical pin g², which is received in an elongated slot g³ in an arm G², pivoted, as shown at g⁴, to the bed-piece A back of the line of the lever G, 55 said arm G² projecting forward over the front edge of said bed-piece A, and having preferably a finger-piece H on its end, either in line with said arm or vertical, as preferred, just back of which this arm G² may have a perforation g⁵ to receive one end of a rod or wire G⁶, whose other end is pivoted, as shown at g⁷, to the upright arm h⁴ of a three-arm finger-piece H', having projecting finger-touches h' h² on the ends of its lower arms and pivoted, 65 as shown at h³, to the front wall of the bed-piece A. Near the end of the lever G, adjacent to the spanner G', there is a vertical tooth or lug G⁴ for engagement at the proper time with the ratchet-teeth c on the adjacent 70 face of the collar D.

In the form of our invention shown in the second sheet of our drawings the lifting-lever G is preferably a single bar moving in suitable bearings, as G⁵ G⁶, in or on the bed-piece A, and carrying a finger-piece H at one end and a spanner G' at its other end, said spanner in this form being designed to straddle the driving-pulley E, and having preferably anti-friction pulleys G⁷ G⁸, mounted, as 75 by screws g⁷ g⁸, on the end of each prong of its bifurcated end to bear against the opposite sides of the said pulley E to reduce noise and friction, as shown, and in this form, in place of the described tooth or lug G⁴, we prefer to employ a spring G⁹, secured to the spanner G' or other convenient portion of the shifting-lever G and terminating in a tooth or lug g⁸ for engagement at the proper time with the ratchet-teeth c on the adjacent 80 face of the collar D. To guard against a too free movement of the shifting-lever G in this form of our device, we prefer to employ a friction-spring I, the free end of which bears against said lever G, while the other end of 85 said spring may be secured at any convenient point, as, for instance, to the bearing G⁶.

The operation of our device will be readily understood from the foregoing description of its construction, taken in connection with 90 the accompanying drawings. We have not deemed it necessary to illustrate or describe

the details of construction of the phonograph proper, such being well known and not of our invention. A slight touch on either of the finger-pieces shown will be sufficient to cause 5 the engagement of the tooth G^4 or g^8 with the ratchet-teeth c on the collar D , and the simultaneous separation of the ratchet-teeth d on said collar and the ratchet-teeth h on the hub F of the driving-pulley E , thereby instantly 10 stopping the revolution of the main shaft and its feed-screw B and permitting the driving-pulley E to run free without interfering with the motive power (whether treadle, electricity, or other means) of the machine, and, similarly, 15 a touch from the opposite direction on the finger-piece H (or on the opposite finger-touch if the finger-piece H' is operated) will as quickly and readily serve to disengage the tooth G^4 or g^8 from the teeth c on the collar D and simultaneously cause the engagement 20 of the teeth d on said collar and the teeth h on the hub F of the driving-pulley E , thereby, as the revolution of the said pulley E has not been interfered with, instantly causing 25 the main-shaft feed-screw B to recommence its revolution at the precise point at which it was stopped.

Our reason for showing two finger-pieces H and H' in the first form of our device is be- 30 cause the piece H may be found more convenient for the dictator or person talking into the machine, while the piece H' may be more accessible to the transcriber, and it will be understood that either form of shifting-lever 35 G may be employed with either form of our device (subject only to necessary details of mechanical construction or adjustment) and that we may employ another or intermediate finger-piece, if desired, on the form of lever 40 G shown in Fig. 6.

A great advantage of our present invention lies in the fact that the shifting-lever and its finger-piece is wholly independent of the main-shaft feed-screw and its connected mech- 45 anism, which insures that the needle (not shown) which indents the hard-wax cylinder C shall always take up its work from the precise point it last indented, and, further, by our construction the finger-pieces are always 50 at the same points in starting and stopping irrespective of the position of the wax-cylinder C at any time, and hence the operator does not need to use the eyes to determine

such points, but can always mechanically find the same with the finger, thereby saving much 55 time, as well as insuring greater accuracy in transcribing.

Having thus described our invention, what we claim as new, and desire to secure by Let- 60 ters Patent, is—

1. In a stop and start device for phonographs, the combination, with the main shaft and a driving-pulley and independent collar thereon, of a shifting-lever carrying devices for engagement with said driving-pulley and 65 independent collar alternately.

2. In a stop and start device for phonographs, the combination, with the bed-piece and supporting-frame, of a main shaft, a driving-pulley on said shaft having ratchet-teeth 70 on its hub and a collar also on said shaft having ratchet-teeth on its opposite faces, and a shifting-lever carrying devices for engagement with said driving-pulley and said collar alternately, substantially as set forth. 75

3. In a stop and start device for phonographs, the combination, with the bed-piece and supporting-frame, of a main shaft, a driving-pulley and independent collar on said shaft and each provided with ratchet-teeth, 80 a shifting-lever movably secured to said bed-piece and free from all connection with the main shaft and its connections, and engaging devices and a finger-piece on said shifting-lever, substantially as set forth. 85

4. In a stop and start device for phonographs, the combination, with the bed-piece, main shaft, and supporting-frame, of a driving-pulley loose on said shaft and having ratchet-teeth on one face of its hub, a collar 90 fast on said shaft and having ratchet-teeth on its opposite faces, and a shifting-lever movably secured to said bed-piece and pro- 95 vided with a spanner for engagement with said driving-pulley and a tooth or lug for engagement with said collar, substantially as set forth.

In testimony that we claim the foregoing we have hereunto set our hands, at Milwaukee, in the county of Milwaukee and State of Wisconsin, in the presence of two witnesses.

HENRY D. GOODWIN.
WILLIAM S. BURNETT.
